UNITED STATES PATENT OFFICE.

THOMAS S. ALEXANDER, OF MERIDEN, CONNECTICUT, ASSIGNOR OF ONE-HALF TO SELAH A. HALL, OF SAME PLACE.

HAME AND RING THEREFOR.

SPECIFICATION forming part of Letters Patent No. 371,726, dated October 18, 1887.

Application filed May 20, 1887. Serial No. 238,835. (No model.)

To all whom it may concern:

Be it known that I, THOMAS S. ALEXANDER, of Meriden, in the county of New Haven and State of Connecticut, have invented a new and useful Improvement in Hames and Rings therefor, of which the following is a full, clear, and exact description.

The rings or terrets used on hames to guide and support the reins are usually of a special construction adapted to such purpose and no other. Thus they are cast and finished in one piece, and include a stem or post and shoulder or flange with attached rivet-shank, all on the exterior of the ring and integral with it. Each hame has a hole in it to receive the rivet-shank or bent portion of the post of the ring for the purpose of attaching the latter by riveting to the hame. This is on many accounts an objectionable construction of the ring and attachment of it to the hame, especially when the hames with their rings, or the rings alone, are of polished metal, inasmuch as the post or projection upon the exterior of the ring, and solid with it greatly interferes with the polishing or finishing of the ring and necessitates a large amount of hand-work. Moreover, in case of breakage of the rings or their necessary removal they can only be replaced by similar rings, which are not always conveniently to be found. Thus general harness terrets cannot be used.

By my invention, however, I am enabled to use and change as required a ring on the hame having no exterior projection which is solid with it—as, for instance, the ring described in my Letters Patent for improvement in harness terrets, No. 350,712, dated October 12, 1886, and which consists of a plain ring having a simple opening in it to provide for its attachment, and which in no way interferes with the finishing or polishing of the ring. This using on the hames the rings or terrets of other parts of a harness will be found exceedingly convenient, and to secure it, as well as to provide for using rings which can be cheaply and highly finished or polished, I not only make use of such plain and simple perforated rings for the hames, but construct the metallic portions of the hames with a post having a shoulder and integral with the upper metallic portion of each hame, so that the perforated ring can be readily attached thereto by simply screwing it onto the integral post of the hame, upsetting or riveting the outer end of said

post on the ring, or both, as found most convenient.

Reference is to be had to the accompanying drawings, forming a part of this specification, in which similar letters of reference indicate corresponding parts in all the figures.

Figure 1 represents a view in perspective of a hame in part, with ring detached, but ready for attachment to the hame by screwing it thereon. Fig. 2 is a similar view showing the ring, partly broken away, as screwed onto the post which is integral with the hame; and Fig. 3, a like view in part, showing the ring as secured to the post of the hame by upsetting or riveting the outer end of the post.

A is the upper metallic portion or section of a hame, having the usual top loop, b, and provided with a post, c, having a shoulder, d, integral with said portion of the hame for attachment of a plain harness-terret ring, B, having a simple perforation, e, in it, such as I have hereinbefore described, said perforation being adapted to receive the post c, so that the ring may be secured thereon and held firm against the shoulder d either by screwing the perforated ring thereon, upsetting the outer end of the post after its insertion through the perforation in the ring, or by both screwing the ring on the post and upsetting the outer end of the latter.

If desired, the shouldered post c may be made with a flange finish, f, where it joins the hame or hame-section A, alike to add strength and to give an improved appearance.

Having thus described my invention, what I claim as new, and desire to secure by Letters Patent, is—

1. The hame or hame section A, provided with a shouldered post, c, integral with the hame and adapted to receive or carry the hame ring or terret, substantially as specified.

2. The combination, with the hame or hame-section A, having a post, c, provided with an inner shoulder, d, both integral with the hame, of the plain ring or terret B, having an aperture, e, the two parts A and B being united with each other by the passage of the post through the aperture in the ring or terret and securing the post therein, essentially as herein described.

THOMAS S. ALEXANDER.
